S. A. SNELL

JACK MECHANISM

Filed Feb. 14, 1922

UNITED STATES PATENT OFFICE.

SAMUEL A. SNELL, OF ST. LOUIS, MISSOURI, ASSIGNOR TO MOON BROTHERS MANUFACTURING COMPANY, OF ST. LOUIS, MISSOURI, A CORPORATION OF MISSOURI.

JACK MECHANISM.

Application filed February 14, 1922. Serial No. 536,521.

To all whom it may concern:

Be it known that I, SAMUEL A. SNELL, a subject of the King of Great Britain, residing at St. Louis, Missouri, U. S. A., have 5 invented a certain new and useful Improvement in Jack Mechanism, of which the following is a full, clear, and exact description, such as will enable others skilled in the art to which it appertains to make and 10 use the same, reference being had to the accompanying drawings, forming part of this application.

My invention relates to operating mechanism for ratchet jacks, such as are commonly used for motor cars, and consists in improvements upon the jack mechanism illustrated in my copending application, Serial Number 524,614.

The objects of my invention are to provide 20 pawl moving means which shall be less expensive to manufacture, easier to assemble, and more definite in their operation than the corresponding means shown in the above-mentioned application and in other 25 jacks of this type which are now on the market.

In the accompanying drawings which illustrate a selected embodiment of my invention,

30 Figure 1 is a side elevation of a jack and operating handle.

Figure 2 is a vertical section on an enlarged scale of the jack operating mechanism.

35 Figure 3 is a similar section but showing the parts in a different operating position.

Figure 4 is a partial elevation of the edge of the jack looking toward the edge upon which the operating handle is 40 mounted.

Figure 5 is a detail section taken on line 5-5 of Figure 2 but with the parts in a different position.

The jack frame 1 is mounted upon a 45 base 2 and is provided with a mechanism housing 3 in which is pivoted at 4 an operating handle 5 and a holding pawl 6. At the inner end of the operating handle 5 is pivoted a lifting pawl 7.

50 Pawls 6 and 7 are provided with downwardly projecting lugs 8 and 9, respectively, which extend into an opening in the lower portion of housing 3. Slidably mounted in an extension 3^a of the housing is a plunger

10 provided with a compressed spring 11 55 tending to thrust the plunger upwardly into a position in which it engages the lugs 8 and 9 of the pawls. Plunger 10 is provided with an eccentric finger 12 adapted to bear against the lower end of housing extension 3^a to hold plunger 10 in a retracted position in which it does not engage either of the pawl lugs. This position is indicated in Figure 5.

Mounted on the pivot 13 of the lifting 65 pawl 7 is a link 14 and uniting the swinging end of this link and the rack engaging portion of pawl 6 is a tension spring 15. Link 14 is provided with a laterally extending toe 16 which engages the front of 70 pawl 7 in such a manner as to constantly push the pawl into engagement with the rack 17. It will be noted that a line drawn from pivot 13 to the engagement of member 15 with the link and thence to the engagement of member 15 with pawl 6 will extend away from the rack and then toward the rack. In other words, link 14 and spring 15 form a jointed tension device for yieldingly moving pawls 6 and 7 toward the 80 rack.

When the jack is to be used for lifting a load, eccentric 12 is positioned as shown in Figure 5, and alternate lifting and lowering of the operating handle will cause 85 pawls 6 and 7 to raise rack 17 in the step-by-step manner common to such jacks. When it is desired to lower a load, eccentric 12 is turned to the position shown in Figures 4, 2 and 3 so that plunger 10 engages 90 the pawl lug which projects downwardly the greatest distance, and yieldingly pushes against the lug in a direction tending to throw the corresponding pawl out of rack 95 engaging position.

Assuming the parts to be in a position shown in Figure 2 and a load upon the top of the rack bar, plunger 10 has thrust pawl 7 away from the rack teeth. Downward movement of the outer end of handle 5 will 100 move pawl 7 upwardly and as plunger 10 is thereby permitted to move upwardly, the latter will engage lug 8 on the holding pawl; further upward movement of pawl 7 will release lug 9 from plunger 10 and 105 permit the link and spring toggle device to function and throw pawl 7 into engagement with a rack tooth. The weight of the

load on pawl 6 will result in sufficient friction between the points of the pawl tooth and engaged rack tooth to prevent spring 11 and plunger 10 from thrusting the pawl 6 out of engagement with the rack. When the upward movement of pawl 7, after engagement with the rack, is sufficient to slightly lift rack 17, this friction is removed and pawl 6 is thrust outwardly by plunger 10. The operating handle is then raised, lowering pawl 7 so that it engages plunger 10 and frees lug 8, permitting the jointed tension device to pull holding pawl 6 back into rack engaging position, the friction between the rack tooth and the lifting pawl tooth being sufficient to prevent spring 11 from throwing the lifting pawl out of rack engaging position.

When the rack is being lowered and is supported upon pawl 7 and the load is removed, the friction between the rack tooth and pawl tooth will be reduced so that spring 11 will thrust plunger 10 upwardly to the position shown in Figure 3, throwing both of the pawls out of engagement with the rack bar and permitting the latter to drop to the position shown, eliminating the necessity of the step-by-step retraction of the rack bar throughout its full length.

It will be noted that the holding pawl 6 is mounted upon a fixed pivot, while the lifting pawl is mounted upon a movable pivot, the moving of which constantly changes the relative positions of the pawl pivots, changes the relative projection of the pawl lugs 8 and 9, and changes the degree although not the direction of the application of the jointed tension device forces. I refer to pawl 17 as the lifting pawl to distinguish it from the holding pawl 6, although when the jack is being lowered, it is not, accurately speaking, a lifting pawl, but a lowering pawl.

Pawls 6 and 7 are preferably formed of steel stampings so as to have a hollow U-shape and when assembled, the bottoms of the U-shaped sections are facing away from each other so that the sides or legs of the U-sections extend toward each other and provide between them a receiving space for link 14 and spring 15. Lugs 8 and 9 are formed by the downwardly projection of the transverse bottoms of the U-sections.

The above described construction eliminates flat springs which are more expensive than coil springs and are subject to undesirable variations in elasticity and are usually more difficult to assemble than coil springs as shown. It will be noted that in a jack of this type there must be a definite cooperation between springs 11 and 15. If one or the other of these springs is too strong or too weak, the pawls will not be actuated to and from the rack bar at the necessary instants. The provision of coil spring 15 and the fastening of it to pawl 6 as shown

enables it to be easily adjusted when necessary to best cooperate with spring 11.

It will be noted that movement of either pawl about its pivot by engagement of its lug by plunger 10 will stretch spring 15 and increase the tension of the latter, thereby increasing the tendency of the spring to move the unengaged pawl toward the rack.

It will be understood that the details of construction illustrated are not essential to the embodiment of my invention as set forth in the following claims.

What I claim is:

1. In a ratchet jack, a frame, a pair of pawls, a coiled spring connected at one end to one of said pawls, and a link connected at its ends to the other end of said spring and to a fixed point on the frame respectively and having a transverse engagement with the other of said pawls.

2. In a ratchet jack, a frame, a lifting rack, a pair of pawls mounted in the frame at the same side of said rack, a link pivoted at one end, a coiled spring having one end secured to the unpivoted end of said link and its other end secured to one of said pawls and tending to pull said pawl toward said rack and to pull said link into a position in which it engages the other of said pawls.

3. In a ratchet jack, a frame, an operating lever fulcrumed between its ends on said frame, a lifting pawl pivoted on one end of said handle, a holding pawl pivoted on said frame, a pawl actuating device comprising a rigid link pivoted at one end on the pivot of one of said pawls and engaging the latter at a point spaced from the pawl pivot, and a coiled spring under tension secured at its respective ends to the unpivoted end of said link and to the other of said pawls at a point on the latter spaced from its pivot.

4. In a ratchet jack, a lifting pawl, a holding pawl, each pivoted near one end, each provided with a projecting lug near its pivoted end and each having a rack engaging tooth at its unpivoted end, an operating lever for shifting said pawls bodily relative to each other, a pressure member engaging one or both of said lugs according to the relative positions of said pawls, a single coil spring secured to one of said pawls, and a link secured to said spring and to a pivot so as to place said spring under tension, said link contacting with the back of the other of said pawls, said spring and link being arranged to pull either of said pawls into rack engaging position when the lug of the other pawl is engaged by said member.

5. In a ratchet jack, a lifting pawl, a holding pawl, each pivoted near one end and having a rack engaging portion spaced therefrom, a tension coiled spring connected to the rack engaging portions of one of said pawls, and a rigid element connected to

said spring and actuated thereby to exert pressure on the other of said pawls at right angles to the axis of said spring.

6. In a ratchet jack, a rack bar, a pivoted holding pawl, a pivoted lifting pawl, a member for shifting the relative positions of the pivots of said pawls, yielding pawl moving means, including a coiled tension spring and a pivoted link arranged end to end and connected and acting to pull one of said pawls forwardly into rack engaging position and thrusting the other of said pawls into similar position, said means being adapted to so move said pawls independently of their relative position.

7. In a ratchet jack, a lifting pawl, a holding pawl, each pivoted near one end, provided with projecting lugs, and having a rack engaging portion spaced therefrom, an operating lever for shifting said pawls bodily relatively to each other, a pressure member engaging one or both of said lugs according to the relative positions of said pawls, and a tension coiled spring and cooperating link connected to said holding pawl and contacting with a face of said lifting pawl adapted to move said holding pawl into rack engaging position when the lug of the lifting pawl is engaged by said member and to move said lifting pawl into rack engaging position when the lug of the holding pawl is engaged by said member.

8. In a jack, a rack column, a pawl for raising and lowering said column, said pawl being channel-shaped in cross section, and a pawl operating element positioned in the channel of the pawl.

In testimony whereof I hereunto affix my signature this 8th day of February, 1922.

SAMUEL A. SNELL.
